UNITED STATES PATENT OFFICE.

ROBERT E. LEE, OF FALL RIVER, MASSACHUSETTS, ASSIGNOR OF ONE-HALF TO JAMES WOOD, OF NEW BEDFORD, MASSACHUSETTS.

BURNER.

Application filed September 7, 1921. Serial No. 499,012.

To all whom it may concern:

Be it known that I, ROBERT E. LEE, a citizen of the United States, residing at Fall River, in the county of Bristol and State 5 of Massachusetts, have invented new and useful Improvements in Burners, of which the following is a specification.

This invention relates to gas burners, and has as its object a burner particularly adapted to be placed in stoves and furnaces of 10 the coal burning type, for the purpose of igniting the fuel whenever a fire is to be kindled. The burner of the present invention is intended, primarily, for the above 15 mentioned purpose and is constructed so as to be placed within a furnace or stove immediately beneath the grate.

An object of the invention is to provide 20 a burner having a plurality of fuel orifices or exit apertures which are protected by means of a suitable hood or other covering means from foreign matter, such as ashes and the like, which falls from the fire-box and has a tendency to clog the jet orifices.

Another object of the invention is to provide 25 the fuel orifices with protecting means of a type having a very narrow top and sloping walls which tend to deflect the foreign matter away from the burner and 30 prevent the matter from collecting upon the hood or deflecting means.

A still further object of the invention is to employ the deflector as means against 35 which the jets may be impinged and laterally deflected so as to produce a flame of greater intensity and area.

The above and other objects of the invention of a more obvious character are accomplished by providing a burner comprising 40 a tube having a plurality of series of jet openings arranged, preferably, in parallel relation. Immediately above the jet openings or apertures and between the series are positioned jet or flame deflecting walls 45 which extend upwardly and over the apertures in diverging directions so as to project the jets issuing from the apertures of the series in opposite directions.

The flame deflecting walls after extending 50 over the apertures continue upwardly in converging directions to meet and thereby to form a hood or protector having downwardly sloping walls with a very narrow top which will not collect soot, ashes and 55 other foreign matter.

The construction above described will be more clear from a reading of the following description of a few embodiments of the invention which are also illustrated in the accompanying drawings. 60

In the drawings:

Figure 1 is a side elevational view of one form which the invention may take.

Figure 2 is a side elevational view of a modified embodiment of the invention. 65

Figure 3 is a cross sectional view of the form shown in Figure 1.

Figure 4 is a cross sectional view of the form of the device shown in Figure 2.

Figure 5 is a plan view of a still further 70 type of burner.

Figure 6 is a side elevational view of the device shown in Figure 5, and

Figure 7 is a cross section of the burner of Figures 5 and 6. 75

Referring to the drawings for a more detailed description, and more particularly to Figs. 1 and 3, 10 indicates a burner tube having two series of gas exit apertures 11 formed in its top wall, the series being arranged in parallel relation as shown clearly in Figure 3. Each series comprises a plurality of apertures extending longitudinally of the burner slightly spaced apart; and between the two series is positioned a rod 12, 80

rectangular in cross section and secured at each end to the tube as by means of a bolt 13. It will be noted that the rod is arranged with one of its edges abutting the surface of the tube between the series of 90

apertures so that it has a wall or side 14 extending upwardly and outwardly over each series of apertures, the two walls 14 extending upwardly in diverging directions. Since the walls are located immediately above the apertures the jets issuing 95

from the latter will be impinged against the walls and deflected laterally at an inclination from the vertical. By thus deflecting the various jets it has been found that 100 the flame is given greater intensity and covers a considerably larger area; the upwardly extending deflecting walls 14 accomplishing this result without materially impeding the passage of the jets, as occurs when a deflecting wall extending in a 105 downward direction over the apertures is employed.

The rod 12 serves not only as a means for directing the flames in a proper and de- 110

sirable direction, but it also protects the apertures from foreign matter and thereby maintains them open at all times. The walls 14 after extending over the apertures meet 5 the upwardly extending and converging sides or walls 15 of the rod, which merge at the top 16. By thus providing a hood or deflector with a very narrow top there is no tendency for foreign matter to collect 10 upon the deflector, since the waste is directed downwardly and away from the burner by the side walls 15.

The form of the device shown in Figures 2 and 4 is slightly different in general construction from the above described embodiment of the invention, but is marked by the same general characteristics, and functions in substantially the same manner. A burner tube 17 is provided with a plurality of 20 spaced nipples 18 arranged in sets of two, spaced apart, the spaces between the sets being, preferably, somewhat greater than the spaces between the individual nipples of each set. Each nipple is formed with a 25 reduced shank 19 fitting within openings 20 in the top of the tube. The shank has a central bore 21 communicating with a pair of upwardly extending and diverging jet orifices 22 which open at their upper ends 30 in the bottom walls 23 of side recesses 24 in the nipples. The top walls 25 of the recesses extend outwardly and upwardly over the orifices 23 and function in the same manner with relation to these orifices as do 35 the walls 14, in the device of Figures 1 and 3, with respect to the apertures 11. The gas jets issuing from the apertures impinge against the wall 25 and are projected laterally at an inclination from the vertical by 40 these walls. Each nipple is formed above the recesses with upwardly converging sides 26 which meet at the top of the nipple to form a very narrow top which will not collect soot and foreign matter. Ashes and 45 the like, falling from the grate, will be directed downwardly by the sides 26 and away from the orifices 22.

If desired, additional hoods or protectors 50 may be placed above each pair of nipples. The hoods are V-shaped in cross section so as to snugly fit the tops of the nipples; and may be held on the nipples by straps 28 extending over the hoods and around the burner tube 17, the ends of the straps being held together as by bolts and nuts 18. These 55 straps may serve the dual function of maintaining the bonnets 27 in position, and also of fixedly holding the nipples within their burner tube openings 20. With respect to 60 this form of the device it should be noted that it is possible to clean any pair of nipples without disturbing the remaining nipples; this may be done by simply loosening a strap which permits the bonnet and 65 pair of nipples to be taken from the tube.

The form of the burner tube shown in Figures 5, 6 and 7 is very similar to the illustration of the invention in Figures 1 and 3. Referring to Figures 5, 6 and 7, it will be noted that the tube 10' is coiled to form a 70 burner of circular outline, and has the spaced series of apertures 11' above and between which is mounted the circular rod 12' held in position by means of screws 13' passing through the rod and burner tube 75 and having substantially squared or rectangular heads 29 fitting in sockets or recesses in the top of the rod.

It is thought that further description of 80 this form of the device is unnecessary, since it functions in the same manner as that disclosed in Figures 1 and 3, and in other construction is identical to that form of the device.

It should be understood that the embodiments of the invention as illustrated and described in detail might be considerably varied without departing from the scope of 85 the invention, which is more clearly defined 90 in the following claims.

I claim:

1. A gas burner for the purpose set forth comprising a horizontal burner tube having two parallel series of spaced gas exit apertures, and deflecting walls positioned 95 between the series extending upwardly in diverging directions over the apertures of each series, said walls serving to protect the apertures from falling foreign matter and to project the jets of the two series at an 100 inclination from the vertical in opposite directions, the walls, after extending over said apertures, continuing upwardly in sharply converging directions, the walls meeting to form a substantially sharp edge 105 whereby the top of the deflector is without sufficient breadth to form a lodging place for soot and other foreign matter.

2. A gas burner for the purpose set forth comprising a horizontal burner tube provided with a series of spaced nipples, each nipple having side recesses with gas exit 110 apertures in their bottom walls, upwardly inclined top recess walls extending over said apertures, the top walls of the recesses in 115 opposite sides of the nipples extending in upwardly diverging directions, thereby serving to project the jets issuing from said apertures at an inclination from the vertical in opposite directions, and also protecting 120 the apertures from falling foreign matter.

3. A gas burner for the purpose set forth comprising a horizontal burner tube provided with a series of spaced nipples arranged in spaced sets of two, the space 125 between the sets being greater than the space between the members of each set, each nipple having side recesses with gas exit apertures in their bottom walls, upwardly inclined top recess walls extending over said 130

apertures, the top walls of the recesses in opposite sides of each nipple extending in upwardly diverging directions, thereby serving to project the jets issuing from said 5 apertures at an inclination from the vertical in opposite directions, and also protecting the apertures from falling foreign matter.

4. A gas burner for the purpose set forth comprising a horizontal burner tube provided with a series of spaced removable nipples, each nipple having side recesses with gas exit apertures in their bottom walls, upwardly inclined top recess walls extending over said apertures, the top walls of the recesses in opposite sides of each nipple extending in upwardly diverging directions, thereby serving to project the jets issuing from said apertures at an inclination from the vertical in opposite directions, and also 15 protecting the apertures from falling foreign matter.

5. A gas burner for the purpose set forth comprising a horizontal burner tube provided with a series of spaced nipples each 25 nipple having side recesses having gas exit apertures in their bottom walls, upwardly inclined top walls extending over said apertures the top walls of the recesses in opposite sides of each nipple extending in upwardly diverging directions, thereby serving to project the jets issuing from said apertures at an inclination from the vertical in opposite directions, and also protecting the apertures from falling foreign matter, the 30 sides of the nipples above said recesses extending upwardly and converging to the top where they meet to form a relatively narrow top.

6. A gas burner for the purpose set forth comprising a horizontal burner tube provided with a series of spaced nipples, each nipple having side recesses with gas exit apertures in their bottom walls, upwardly inclined top walls extending over said apertures, the top walls of the recesses in opposite sides of each nipple extending in upwardly diverging directions, thereby serving 45 to project the jets issuing from said apertures.

tures at an inclination from the vertical in opposite directions, and also protecting the 50 apertures from falling foreign matter, and at least one deflector hood above said nipples serving to prevent the ingress of foreign matter between the nipples and into said apertures.

7. A gas burner for the purpose set forth comprising a horizontal burner tube provided with a series of spaced removable nipples, each nipple having side recesses with gas exit apertures in their bottom walls, upwardly inclined top walls extending over 60 said apertures, the top walls of the recesses in opposite sides of each nipple extending in upwardly diverging directions, thereby serving to project the jets issuing from said 65 apertures at an inclination from the vertical in opposite directions, and also protecting the apertures from falling foreign matter, at least one deflector hood above said nipples serving to prevent the ingress of foreign 70 matter between the nipple and into said apertures, and a single means serving to hold both said hood and said nipples in position on said tube.

8. A gas burner for the purpose set forth comprising a horizontal burner tube provided with a series of spaced removable nipples, each nipple having side recesses with gas exit apertures in their bottom walls, upwardly inclined top walls extending over 80 said apertures, the top walls of the recesses in opposite sides of each nipple extending in upwardly diverging directions, thereby serving to protect the jets issuing from said apertures at an inclination from the vertical in 85 opposite directions, and also protecting the apertures from falling foreign matter, at least one deflector hood above said nipple, serving to prevent the ingress of foreign matter between the nipple and into said 90 apertures and a single means serving to clamp both said hood and said nipples in position on said tube.

In testimony whereof I have hereunto set my hand.

ROBERT E. LEE.
